DESIGN FOR A COMBINATION ASHTRAY AND RECEPTACLE

Charles Julius Kuntz, New York, N. Y.

Application December 5, 1936, Serial No. 66,338

Term of patent 14 years

To all whom it may concern:

Be it known that I, Charles Julius Kuntz, a citizen of the United States and a resident of New York, in the county of New York, in the State of New York, have invented a new, original, and ornamental Design for a Combination Ashtray and Receptacle, of which the following is a specification, reference being had to the accompanying drawing, forming a part thereof.

Figure 1 is a front elevational view of a combination ashtray and receptacle, Figure 2 is a plan view of the same, and Figure 3 is a perspective view of the same, showing my new design.

I claim:

The ornamental design for a combination ashtray and receptacle, as shown.

CHARLES JULIUS KUNTZ.
